(57) **CLAIM**

The ornamental design for a display device with alternate attachment means assembly, as shown and described.

DESCRIPTION

FIG. 1 is a top view of a display module showing our new design;

FIG. 2 is a side elevation view thereof;

FIG. 3 is a top perspective view thereof;

FIG. 4 is a top perspective view of the display module with its associated clip attachment means;

FIG. 5 is a top perspective exploded view thereof;

FIG. 6 is a top perspective view of the display module with its associated flexible jacket attachment means;

FIG. 7 is a top perspective exploded view thereof;

FIG. 8 is a top perspective view of the display module with its associated wrist attachment means; and,

FIG. 9 is an top perspective exploded view thereof.

The broken lines are included for the purpose of illustrating a portion of the display device with alternate attachment means assembly that forms no part of the claimed design.
